UNITED STATES PATENT OFFICE.

FRANK J. KEIL, OF NEW YORK, N. Y.

DESIGN FOR A TRIMMING FOR WEARING-APPAREL.

58,578.

Specification for Design.

Patented Aug. 2, 1921.

Application filed May 28, 1921. Serial No. 473,406. Term of patent 3½ years.

To all whom it may concern:

Be it known that I, FRANK J. KEIL, a citizen of the United States, residing in the city, county, and State of New York, have invented a new, original, and ornamental Design for a Trimming for Wearing-Apparel, of which the following is a specification, reference being had to the accompanying drawing, forming part thereof, and in which—wearing apparel, showing my new design, the same indicating the scallops loose at their lower embroidered edges and lined with other material, different in color or texture, the same showing at the bottoms of the scallops.

Fig. 2 is a transverse sectional view of the same.

I claim:—

The ornamental design for a trimming for wearing apparel as shown.

FRANK J. KEIL.
